DESIGN FOR A PIPE CASE

Walter O. Briggs, Jr., Detroit, Mich.

Application November 21, 1934, Serial No. 54,101

Term of patent 3½ years

To all whom it may concern:

Be it known that I, Walter O. Briggs, Jr., a citizen of the United States, residing at Detroit, in the county of Wayne and State of Michigan, have invented a new, original, and ornamental Design for a Pipe Case, of which the following is a specification, reference being had therein to the accompanying drawing, forming a part thereof, in which

Fig. 1 is a perspective view of a pipe case embodying my new design and illustrating the foldable sections thereof in extended position.

Fig. 2 is a perspective view of the pipe case illustrating the sections in folded position.

I claim:

The ornamental design for a pipe case, substantially as shown and described.

WALTER O. BRIGGS, JR.
